UNITED STATES PATENT OFFICE.

CAMILLE HENRI FUCHS, OF NEW YORK, N. Y., ASSIGNOR TO THE MAURICE LEVY CO.,
INC., OF NEW YORK, N. Y., A CORPORATION OF NEW YORK.

METHOD OF FINISHING FLAT POWDER PUFFS AND IMPROVED PUFF.

Application filed November 20, 1926. Serial No. 149,629

My invention relates to a new and improved method of finishing flat powder puffs and a new and improved finished flat powder puff.

5 One of the objects of my invention is to provide a method whereby a powder puff of the flat type can be finished very neatly and quickly.

10 Another object of my invention is to provide a finished powder puff which shall be of superior appearance, it being understood that the claims for the article are not limited to the method of making the same.

15 Other objects of my invention will be set forth in the following description and drawings which illustrate a preferred embodiment of my invention, it being understood that the above general statement of the objects of my invention is intended merely to generally explain the same and not to limit it in any manner.

Fig. 1 is a top view of a puff to be finished.

Fig. 2 shows the puff illustrated in Fig. 1 after the first operation has been performed.

25 Fig. 3 is a bottom view showing the finished puff.

Fig. 4 is an end elevation of Fig. 1.

Fig. 5 is an end elevation of Fig. 2.

Fig. 6 is an end elevation of Fig. 3.

Fig. 7 is an enlarged view of the device shown in Fig. 1.

30 Fig. 8 illustrates in detail the first operation in finishing the puff.

Fig. 9 is a detail enlarged view showing how the threads are connected to the peripheral stitches adjacent the pile surface of the puff.

Fig. 10 is a detail view of the finished puff.

Fig. 11 is a view of the needle utilized in finishing the puff.

Flat puffs 10 of the type to which this invention is directed and which are usually employed in vanity cases or compact boxes consist of a single layer of pile fabric F which is stitched to a base portion made of one or more layers of fabric so as to provide a relatively stiff base. This stitching is accomplished by means of an overstitch machine, such as a machine of the "Merrow" type, and when the stitching operation has been completed, four threads are left projecting or hanging from the edge of the puff.

Heretofore, it required considerable time to give the puff a finished appearance, and these four hanging threads were disposed of in various ways.

As shown in Figs. 1 and 4, when the stitching operation has been finished, three threads 12 remain dangling from the bottom face of the puff and one thread 11 hangs from the top face of the puff. The last loop 11^a of the top thread 11 is engaged by the shank of the needle 14 and the thread 11 is then pulled through the edge of the puff so that the three threads 12 and the fourth thread 11 all hang downwardly from the same side of the puff as shown in Fig. 5, for example. The needle 14 is provided with a rear springy extension 15 and with an eye 16 which has a space 17 between it and the rear extension 15. Hence, it is very easy for a skilled operator to pass the three threads 12 and the fourth thread 11 into the eye 16 of the needle 14. The needle 14 is then forced to the edge of the fabric F and underneath the overstitched loops 13, as shown in Fig. 9, for example, so that the four threads before mentioned are pulled underneath several of the loops 13. It is now very easy for the operator to cut off the projecting ends of the four threads, thus leaving the four threads permanently engaged by the loops 13.

A puff thus made has a very neat and well finished appearance because the ends of the four threads cannot be detected by casual observation.

It will be noted that the ends of the four threads are engaged by the loop-like stitches at the bottom of the puff, so that there is no disagreeable contrast formed between the colored threads 11 and 12 and the base or top of the puff, which is usually colored.

I have shown a preferred embodiment of my invention, but it is clear that numerous changes and omissions could be made without departing from its spirit.

I claim:

1. The method of finishing a flat powder puff having threads forming loop-like stitches at the periphery thereof, said stitches terminating in three threads hanging from the bottom face of the puff and a thread hanging from the top face of the puff, which consists in pulling said top thread through the

edge of the puff so that each of the before mentioned four threads hang from the bottom face of the puff, and then causing free ends of said four threads to engage some of said stitches at the bottom face of the puff.

2. A finished flat powder puff having threads forming loop-like stitches at the pe-

riphery thereof, the free ends of said threads being all on the same side of the said puff, said free ends being engaged by some of said loop-like stitches. 10

In testimony whereof I affix my signature.

CAMILLE HENRI FUCHS.
